UNITED STATES PATENT OFFICE.

HAROLD M. PORTER, OF HAGERSTOWN, MARYLAND, ASSIGNOR TO THE PORTER
CHEMICAL COMPANY, A CORPORATION OF MARYLAND.

EDUCATIONAL DEVICE.

1,350,237.

Specification of Letters Patent. Patented Aug. 17, 1920.

Application filed December 3, 1919. Serial No. 342,054.

To all whom it may concern:

Be it known that I, HAROLD M. PORTER, a citizen of the United States, residing at Hagerstown, county of Washington, State of Maryland, have invented certain new and useful Improvements in Educational Devices; and I do hereby declare the following to be a full, clear, and exact description of the invention, such as will enable others skilled in the art to which it appertains to make and use the same.

This invention relates to educational devices designed to furnish instruction to children while entertaining them. It has in view to provide a knock-down or collapsible working outfit or laboratory whose parts can be readily assembled for use to form a firm and stable structure and provided with the necessary features to carry out conveniently the operations and manipulations involved in such a device and, at the same time, to be readily taken apart and to permit the apparatus and material employed to be packed away and stored in a compact form, safely and without liability to breakage of the fragile articles forming part thereof.

An outfit of the character contemplated under this invention comprises a box or receptacle having a cover adapted to be swung open to a vertical or upright position, that is, at right angles to the body of the box and held in such position against further outward movement, a removable tray for carrying vials, test-tubes or similar articles arranged to lie horizontally within the box and, when the outfit is to be put into working shape, to be placed into an upright position, one of its ends being adapted to engage a receiving part or guide at one end of the box body and in such relation to the opened box cover as to retain the same in its opened position, thereby forming with the same a working laboratory or work shop corner, the inner bottom of the box body serving as a table on which the various operations may be performed, the tray serving as a shelving for vials containing reagents and chemicals and as a test tube rack.

The interior of the box is fitted with cleats near one end, which cleats not only serve to support the tray when in its horizontal position within the box, but to form with one end of the box the receiving part

or guide for the tray when installed in its upright position.

Where the tray is made shorter than the interior of the box the cleats are rabbeted or stepped at their tops to both support the tray and to retain it against shifting or longitudinal movement. Where in a laboratory dry reagents and chemicals are used, the same may under my invention be stored in receptacles of the same height as the supporting cleats. Thereby they coöperate with said cleats in supporting the tray when packed in the box. To prevent the receptacles from shifting and to hold them in position, one part of the invention contemplates the use of a plate of less length than that of the box and having an upright flange or guard to be placed in the bottom of the same, the upright guard or flange serving to hold the receptacles in place and to divide the interior of the box into two compartments.

Other features of the invention will become clear from the following detailed description, and the appended claims.

In the accompanying drawing I have represented an embodiment of my invention as applied to a portable outfit for chemical operations in the form of a knock-down laboratory intended mainly for juvenile use.

In this drawing—

Figure 1 represents a perspective view of the same opened, with the combined tray and vial shelf and test tube rack in its horizontal position;

Fig. 2 is a similar view with said tray removed;

Fig. 3 is a similar view with all the parts of the laboratory assembled for use;

Fig. 4 is a vertical longitudinal section on a reduced scale of the laboratory in operative position; and

Fig. 5 is a detail view in vertical section.

As illustrated in this drawing, the new device comprises a box or case made of any suitable, preferably light, material such as wood or card board, to the body portion 1 of which is hinged at the top of one of its longer side walls a cover 2, adapted to be swung open and to be retained in a vertical or upright position and against further outward movement by any suitable stay or detent, such as a flexible retaining band or cord 3.

Within the body of the box, at a point near one of its end walls 4 on each side wall 5, 6, is arranged an upright cleat 7, the two cleats 7, 7 forming with the end wall 4 a receiving part in the form of a guide way or socket whose function will hereinafter appear. At the two inner corners at the opposite end of the box are arranged or formed cleats 9, 9, the upper surfaces of said cleats forming with the upper surfaces 11, 11, of the cleats 7, 7, in the same horizontal plane with the former, a support for a tray B, when packed away in the interior of the box, as shown in Fig. 1. If, as shown in the drawings, said tray is of a length less than that of the box interior, means are provided for preventing the lengthwise shifting of the tray, which means, in the present instance consist in forming a rabbet or step 11 in each of the cleats 7 at their top, the forward end of the tray B fitting into said rabbets of the stepped cleats 7 at its lower edge and its length substantially occupying the space between the end wall 8 of the box and the vertical surfaces of the rabbets, as seen in Fig. 1.

Fitting within the body of the box is a plate 12 (Figs. 1, 2 and 4) formed with an upright guard in the form of a flange 13, side flanges 14, 14, at right angles thereto, being formed on said upright flange at both sides thereof. The said flanged plate 12 is preferably made removable from the box interior and of a length substantially equal to that of compartment 16 in which it is situated. This plate, which is preferably made of impermeable or oiled or glazed card board or of thin sheet metal, not only serves to partition off the interior of the box into two compartments 15 and 16 by means of flange or guard 13, but also as a working table when the compartment 16 has been emptied of its contents packed therein when the case is not in use. On the working table thus provided the experiments and reactions for which the outfit is designed may be conveniently carried out without injuring or defacing the material of the box.

The cover 2 of the box A is recessed, as shown and on the inner surface of its top are arranged holders for implements and apparatus when the laboratory is in use, such holders being in the present example made by a band of flexible material, such as thin oiled card board, leather, or the like 16, secured to the cover at intervals, thereby forming loops 17, into which such implements may be slipped. A strip of impermeable sheet material 18 such as oiled card board, may be applied to the cover behind and below the loops, as shown.

The tray B serves the purpose of a combined packing and storing receptacle for fragile vials and test-tubes and a test tube

rack and shelving for reagent bottles or vials 40. It consists in a rectangular frame 19 which is not attached to the same in any way, so that it may be removed bodily therefrom for the purposes hereinafter set forth. It has a bottom 20 of stiff sheet material, such as oiled or glazed card board, secured thereto. To this bottom are attached at intervals flanged shelves 21, made in the present instance of sheet material, such as oiled or glazed card board bent to the form of rectangular troughs secured in any suitable manner, as by gluing to the bottom 20. When the tray is in its horizontal position, as in Fig. 1, the upper flanges 22 of the shelves 21 serve to retain the reagent bottles or vials in position and against being jolted out of position while when the tray B is in the vertical position represented in Figs. 3 and 4, they act as fenders to hold said bottles or vials in place. At the inner end of the tray, constituting its bottom, when in an upright position, is arranged a holder 23 for test tubes 41, consisting, as shown, of a strip of sheet material, such as thin oiled or glazed card board or the like, bent in form of a trough, whose upright side 24 (when the tray is in the horizontal position of Fig. 1) is formed with perforations 25 at suitable intervals, such perforations serving to receive and retain test tubes when in use and when the tray occupies the upright position shown in Fig. 3. This holder is secured to the bottom 20 of the tray in the same manner as the shelves 21, or in any other suitable way. When the tray B is packed away in the box for shipping, as seen in Fig. 1, the vials and the test tubes are secured against movement by strings or cords 45 passing around them and through the bottom of the tray. These cords are removed or severed when the articles are to be used.

The outfit thus described is adapted for use as follows, it being assumed that the box is closed and that the reagents, instruments, implements and other articles constituting the contents of the case are packed in the same in the manner indicated in Fig. 1 in connection with Fig. 2, that is to say, boxes 26 containing dry chemicals, powders and the like in the space or compartment 16, and various apparatus, such as a gas generating bottle 27, a test tube brush 28, stirring rods 29, a pestle 30, and other devices for manipulating the reagents and test tubes, in compartment 15 separated from compartment 16 by the flange 13, the tray B being placed horizontally over the said compartments in the position shown in Fig. 1. On opening the case and swinging the cover into the upright position indicated in the drawings, the same is held against swinging farther backward by the stay band 3. The tray B which, as above ex-

plained is entirely detached from the box is now removed from the box and, being tilted into an upright position with the end carrying the test-tube holder 23 downward, is inserted into the guide-ways or, more specifically, slide ways formed between the cleats 7 and the end 4 of the box. The shelved tray is thereby secured to the body portion 1, with its interior or open side 10 facing said body portion. It is thereby not only held in its upright position, with the necessary firmness, but also serves as a check or guard for the cover 2, as seen in Figs. 3 and 4, locking the same in its upright position. To form a still stiffer connection for these parts, the tray is provided at its bottom at the edge which comes adjacent to the cover 2, in the position in Fig. 3, with a swinging hook 31, adapted to engage with a pin 32 on the inner surface of the end flange 33 of cover 2, as shown in Fig. 5.

A number of the implements and articles, such as a test-tube clamp 34; test-tube brush 25 28, stirring rods 29, a blow pipe 35, a spoon 36 etc. are now taken out of the receptacle compartment 15, and inserted into the holding loops of the cover 2, so as to disencumber the plate 12 and permit the same to be 30 used as a laboratory table. The parts being thus assembled, there is formed a complete laboratory corner of reduced size in which all of the chemical processes and manipulations may be carried out with convenience, 35 all of the reagents, chemicals, etc., being in a convenient position for use and with respect to the laboratory table. The laboratory in miniature thus formed is also stable and not liable to be disarranged, the tray B serving 40 not only the purposes of shelving for reagents and test tube rack, but also as a stay for the cover 2 to retain the same in its vertical position, and when the operations involve the use of a lamp 37, to protect the 45 flame against sudden gusts of air.

The boxes or smaller receptacles 26, containing dry chemicals are preferably of a height equal to the height of the bottom of the tray above the bottom of the box when 50 packed away in a horizontal position in the box body, thereby forming a support for the said tray in coöperation with the cleats 7, 7.

When arranged in sufficient number, as in the example represented in the drawing (Figs. 2 and 3) they serve as a stop for the removable flanged plate 12, and when the said plate is of the same length as the compartment 15, as in the case illustrated in the drawing, the said receptacles combine with 60 the flange 13 on said plate to form two fixed compartments 15 and 16, one for the said receptacles and the other for the articles to be stored when the laboratory is dismantled and packed away, the flange 13 being thus 65 held stationary. The said plate 12 is slid-

able and thereby adapted to adjust the compartment 15 to a varying number of receptacles or other articles to be received by the same. The space between the tray B and the end of the box where the cleats 7, 70 7 are situated serves as a receptacle for articles of a larger height than those packed in or under the tray, for example, a mortar 46 and the like. The total length of the tray is preferably made of a length substantially equal to the depth of the box interior plus the height of the under side of 75 the cover when raised into the upright position.

What I claim is:

1. In a device of the character set forth, a box provided with a receiving part at one of its walls, in combination with a removable and detached tray arranged to fit into the box interior and to lie flat therein when closed and so formed at one end as to fit and engage the receiving part when in an upright position. 80

2. In a device of the character set forth, a box provided with a slide way at one of its inner walls, in combination with a transversely partitioned tray arranged to lie flat in the box and having sides of a depth substantially equal to the width of the slide way, whereby the tray may be caused to engage said slide way, being held thereby in an upright position to serve as a shelving. 85

3. In a device of the character set forth, a box provided on its interior with upright cleats at opposite sides near one end wall, 100 said cleats forming guide ways with said end-wall, in combination with a transversely partitioned tray, adapted to lie horizontally in the box and so formed at one end as to fit into and engage the guide ways when tilted into an upright position. 105

4. In a device of the character set forth, a box interiorly provided with upright cleats forming guide ways with one end wall, said cleats being rabbeted at their tops to form bearing surfaces and vertical retaining shoulders; additional bearing surfaces at a point away from the guide ways and substantially at a level with the bearing surfaces of the cleats, in combination with 110 a tray of a length to occupy the space between said upright bearing surfaces and the opposite end wall of the box, and of such cross-section as to fit into said guide ways when it is tilted into an upright position. 115

5. In a device of the character set forth, a body-portion serving as a receptacle and a work table, in combination with a tray arranged to fit into the interior of said body-portion and to lie flat therein with its interior facing upward when closed, and means for securing said tray with its interior facing toward the said body portion when in an upright position. 125

6. In a device of the character set forth, 130

- a body portion serving as a receptacle and a work table, in combination with a transversely partitioned tray arranged to fit into the interior of said body-portion and to lie flat therein with its interior facing upward when closed, and means for securing said tray with its interior facing toward the said body-portion when moved into an upright position.
- 10 7. In a device of the character set forth, a rectangular box body, a cover hinged thereto, means to prevent said cover from swinging outward beyond an upright position, and a slide way at one end of the box 15 and in line with the contiguous end of the cover, in combination with a tray adapted to fit into and engage the slide way when upright, whereby the said tray extends into the path of the cover and retains the same 20 in its upright position.
8. In a device of the character set forth, a box body, a cover hinged thereto, means to prevent said cover from swinging outward beyond an upright position and a 25 guide way at one end of the box and in line with the contiguous end of the cover, in combination with a tray adapted to fit and engage the guide way when upright, and a locking device between the tray and the 30 cover, whereby said tray extends into the path of the cover, retaining the same in its upright position, the two parts being locked in this position.
9. In a device of the character described, 35 a rectangular box provided with a cover hinged thereto, and means for preventing the cover from swinging outward beyond an upright position, in combination with a tray, means to alternately support the tray 40 in its horizontal position in the box or to secure it in a vertical position and adjacent to the under side of the box cover when swung into an upright position, whereby the tray serves to hold the cover in its 45 upright position, the tray being of a length equal to the interior depth of the box body plus the height of the upturned cover.
10. In a device of the character set forth, 50 a box, in combination with a plate shorter in length than the interior of the box body and serving as a combined partition and working-table, said plate resting on the bottom of the box interior and provided at one end with an upright flange or guard arranged to form one wall of a compartment 55 in the said box interior.
11. In a device of the character set forth, 60 a box in combination with a plate shorter in length than that of the box interior, and provided with an upright guard dividing the box interior into two compartments, a tray support arranged in the compartment in which the plate is situated, and a plurality of receptacles in the other compartment
- substantially equal in height to the said 65 tray-support, thereby serving to coöperate with the latter to support the tray in a horizontal position.
12. In a device of the character set forth, 70 a convertible tray and laboratory shelving, consisting in a rectangular body having transverse partitions substantially at right angles thereto and formed with flanges which are at the top of the tray when in a horizontal position and at the front when 75 upright.
13. In a device of the character set forth, 80 a convertible tray and laboratory shelving, consisting in a rectangular body having transverse partitions substantially at right angles thereto and formed with flanges which are at the top of the tray when in a horizontal position and at the front when upright, the partitions being formed of sheet-material bent into trough shape, one 85 side of the trough-shaped partition being secured to the tray-bottom.
14. In a device of the character set forth, 90 a convertible tray and laboratory shelving consisting in a rectangular body having transverse flanged partitions formed of trough-shaped sheet material and having secured at one end thereof an inverted trough-shaped body of sheet material perforated at its face transverse to the body of the tray 95 for the reception of test-tubes, when the tray is upright.
15. In a device of the character described, 100 the combination, with a box having a cover hinged thereto, of a tray fitting within said box and movable into an upright position within said box when the cover is lifted, and means operable when said tray is in such upright position to lock the cover to the tray.
16. A knock-down miniature laboratory 105 device comprising in combination, a table or bench member, a wall member hinged thereto and capable of being swung into a position at right angles thereto, and a second wall member capable of being positioned at 110 right angles to both said table or bench member and the first wall member, and means preventing dislocation of the aforesaid parts with relation to each other when so positioned, substantially as set forth.
- 115 17. A knock-down miniature laboratory device comprising in combination, a horizontal table or bench member, a plurality of wall members adapted to be adjustably secured to said table or bench member and to 120 each other in upright position to laterally shield a corner of said table, and shelving means carried by one of said wall members, substantially as set forth.
18. A knock-down miniature laboratory 125 device comprising, in combination, a normally horizontal table-providing member, two movable wall members which can be po-

sitioned vertically with respect to said table-providing member and which, when so positioned, coöperate to laterally shield a corner of the same, and means for releasably holding the parts in the relation specified, said wall members being collapsible upon said table-providing means when released, substantially as set forth.

19. A knock-down miniature laboratory device, comprising, in combination, a normally horizontal table-providing member, two movable wall members which can be positioned vertically with respect to said table-providing member and which, when so positioned, coöperate to laterally shield a corner of the same, means for releasably holding the parts in the relation specified, said wall members being collapsible upon said table-pro-

viding means when released, and shelving means on one of said walls, substantially as set forth.

20. In a collapsible laboratory, a part serving as a receptacle for the articles employed in the laboratory and as a work table, and a part serving as a cover therefor, in combination with a shelved removable and detached part adapted to be stored in the part serving as a receptacle and means to lock the same in such relation to the part serving as a cover, that it retains the same in its opened position and forms therewith and with the part serving as a receptacle a laboratory corner.

In testimony whereof I hereunto affix my signature.

HAROLD M. PORTER.
